UNITED STATES PATENT OFFICE.

ALFRED J. KIECKHEFER, OF MILWAUKEE, WISCONSIN, ASSIGNOR TO NATIONAL ENAMELING & STAMPING COMPANY, OF MILWAUKEE, WISCONSIN.

DESIGN FOR A HOLDER FOR OIL-STOVE RESERVOIRS.

56,928.

Specification for Design.

Patented Jan. 18, 1921.

Application filed August 23, 1920. Serial No. 405,556. Term of patent 14 years.

To all whom it may concern:

Be it known that I, ALFRED J. KIECKHEFER, a citizen of the United States, residing at Milwaukee, in the county of Milwaukee and State of Wisconsin, have invented a new, original, and ornamental Design for a Holder for Oil-Stove Reservoirs, of which the following is a specification, reference being had to the accompanying drawing, forming part thereof.

Figure 1 represents a plan view of a holder showing the features of my design.

Fig. 2 is a side elevational view of the same, and

Fig. 3 is a longitudinal sectional elevation of the holder.

I claim:

The ornamental design for a holder for oil stove reservoirs, as shown.

In testimony that I claim the foregoing I have hereunto set my hand at Milwaukee, in the county of Milwaukee and State of Wisconsin.

ALFRED J. KIECKHEFER.
